Application July 29, 1943, Serial No. 496,552

10 Claims. (Cl. 178—22)

1

This invention relates to printing telegraph systems and apparatus and particularly to a system and apparatus for the transmission and reception of secret or confidential telegraph messages.

Signalling systems are desirable for naval, military and civil purposes wherein it is required that messages be rendered unintelligible to persons unauthorized to receive them. Surreptitious interception of messages may be accomplished, for example, in the case of wire communications by tapping signal wires, and in radio communication by means of receiving apparatuses tuned to the proper frequencies.

The principal object of the present invention is to provide simple, compact and reliable facilities in telegraph systems and apparatus for rendering messages unintelligible to unauthorized persons.

Another object of the invention is to provide a system and apparatus for precluding the unauthorized interception of intelligible messages by mechanical operation established in response to the respective control conditions.

A further object of the invention is to provide enciphering and deciphering instrumentalities which are readily adaptable to commercially available printing telegraph apparatus.

In order to encipher messages by the present system and apparatus, the elements of the code combinations of the original, intelligible message are combined with the elements of code combinations provided by a key tape or other control mechanism. In such arrangement, opposite conditions, that is, with one element of the original code combination marking and with the corresponding element of the key code combination spacing, produce a marking signal. Like conditions, however, with both elements marking or both elements spacing, produce spacing signals. This presumes, of course, that each of the elements of the respective code combinations are related to each other. That is, the No. 1 element of the original code combination is combined with the No. 1 element of the key code combination, and so forth. To take a specific illustration, let it be assumed that it is desired to encipher the character "R" which in the Baudot code is composed of spacing, marking, spacing, marking, and spacing conditions. Let it be further assumed that the key tape with which the particular enciphering operation is to be performed occupies a position whereat it is conditioned for producing the letter "Y" combination which in 55

2

the Baudot code is composed consecutively of marking, spacing, marking, spacing, and marking conditions. Under the assumed conditions, the enciphering operation would result in the production of an all marking or "letters" combination, since in this particular illustration opposite conditions of all the related elements of "R" and "Y" code combinations are provided. This will be readily apparent from the following chart wherein the letter "M" indicates a marking condition and the letter "S" indicates a spacing condition.

	1	2	3	4	5
Original Signal "R".....		S	M	S	M
Key Signal "Y".....	M	S	M	S	M
Enciphered Signal "Letters".....	M	M	M	M	M

26 It is understood that both the transmitting and receiving end of a telegraph line will be equipped with identical key tapes or other control mechanisms which during message transmission will occupy identical positions. During 25 transmission the key tapes or other control mechanisms are advanced between characters to modify the key signal, but both tapes occupy the same corresponding position at all times. A station which receives enciphered signals is thus 30 enabled to decipher the unintelligible signals transmitted over the telegraph line by combining enciphered signals with key signals provided by its key tape or other control mechanism.

To illustrate a deciphering operation, the example given above in connection with the enciphering operation will be continued and it will 35 be assumed that a receiving station received the enciphered signal; namely, "Letters." The "Y" combination provided by the key tape or other control mechanism at the receiving station can now be combined with the received "Letters" combination to decipher the enciphered signal to thereby reproduce the original signal "R," as 40 clearly shown in the following chart:

	1	2	3	4	5
Enciphered Signal "Letters".....	M	M	M	M	M
Key Signal "Y".....	M	S	M	S	M
Original Signal "R".....	S	M	S	M	S

A more complete understanding of the invention may be had from the following description taken in conjunction with the accompanying drawings, wherein:

Fig. 1 is a plan view of the receiving printer

embodying the deciphering device according to the present invention;

Fig. 2 is a sectional view taken on line 2—2 of Fig. 1;

Fig. 3 is a front elevational view, partly in section, taken on line 3—3 of Fig. 2;

Figs. 4, 5, and 6 are views illustrating the various operational positions of the deciphering device;

Fig. 7 is a plan view of the keyboard controlled enciphering device according to the present invention;

Fig. 8 is a sectional view taken on line 8—8 of Fig. 7;

Figs. 9, 10, and 11 are views illustrating the enciphering device in its various operational positions; and

Fig. 12 is an electrical circuit diagram of the telegraph system embodying the present invention.

The deciphering mechanism according to the present invention is illustrated in Figs. 1, 2, and 3 as applied to a type wheel printer of the type shown in copending application Serial No. 397,193, filed June 9, 1941, by W. J. Zenner. The printer framework is indicated at 11 and comprises side frames 12 and 13. Mounted on side frames 12 and 13 are journal brackets 14 and 15 which support the main cam shaft 16. Also spanning the frames 12 and 13 is a cross bar 17. A plate 18 also spans the side frames 12 and 13 and carries a series of five electromagnets 19, 20, 21, 22, and 23, which constitutes part of the deciphering mechanism according to the present invention. Journalled in the side frames 12 and 13 and extending therebetween is a pivot shaft 24. Pivotally carried on the pivot shaft 24 substantially midway between the frames 12 and 13, is a printing arm 25 which carries at its extremity (the left end, as viewed in Fig. 2), a platen member 26.

Platen 26 cooperates with a type segment 27 fixed to a type wheel shaft 28 journalled in a bearing 29 mounted in plate 30 which spans the frames 12 and 13. The right-hand end of the type wheel shaft 28 is carried in a bearing 32 mounted on a bracket 31 fixed to the plate 30. The type segment 27 is provided with four rows of type faces, and a shift mechanism is exemplified by a plurality of stop bars 33, provided for controlling the shifting movement of the type segment 27 to effect printing from the various rows of type. The bracket 34 is provided for guiding and supporting the tape between the platen 26 and the type segment 27. A spring 35 normally biases the type or printing arm 25 downwardly to hold the platen 26 free from the type segment 27. The printing operation is effectuated through the instrumentality of the vertical link 36 extending between the printing arm 25 and a printing cam (not shown) carried on the main shaft 16. Carried in brackets 37 and 38 mounted on bar 17 is a pivot shaft 39 on which are pivotally carried a series of selector levers 41 to 45. Each of the levers 41 to 45 is provided with a cam follower projection 46 which cooperates with the periphery of an associated selector cam 47. There are five such cams 47, one associated with each of the five selector levers 41 to 45. The cams 47 are of similar cam contour but are displaced on the shaft 16 angularly so that the cam projections 48 are disposed in a helically arranged series whereby coaction with the cam followers 46 will occur in a sequential manner as the series of cams 47 rotates in synchronism

with the speed of code impulsing. The levers 41 to 45 are normally biased in a clockwise direction about the pivot shaft 39 by individual springs 49.

Each of the levers 41 to 45 extends leftwardly (as viewed in Fig. 2) and carries a vertically projecting portion 51. The extremities 52 of the levers 41 to 45 cooperate with a shoulder 53 on an associated selector bar 54. Bars 54 are disposed vertically in the printer mechanism and are mounted on a shaft 55. Each of the bars 54 is provided with a slotted hole 56 cooperating with the shaft 55 so that an individual spring 57 associated with each of bars 54 tends to hold the bar 54 in its vertical position against the bottom of the slot 56. The vertical bars 54 are provided with a series of notches on one edge thereof and cooperate with a plurality of function bars 58 in the manner described in said copending Zenner application.

Positioned above the series of portions or lugs 51 and cooperative therewith in a manner which will presently appear, is a corresponding series of pairs of depending levers 61 and 62 pivotally carried on a shaft 63 suitably journaled above the printer frame. Lever arms 61 and 62 are normally biased toward each other by a common spring 64 extending therebetween. A bar 65 is provided to limit the movement of levers 61 and 62 under certain operating conditions. Levers 61 and 62 are also provided with confronting projections 66 and 67, respectively. Operatively positioned between the projections 66 and 67 is the laterally disposed extremity 68 of the depending arm of a bell crank lever 69, also pivotally carried on the shaft 63. Also operatively positioned between the projections 66 and 67 is the laterally extending end or extremity 71 of an armature 72 of an electromagnet 73. The armature 72 is normally biased in a clockwise direction about pivot 70 by a spring 74. The magnet 73 is a single line magnet which responds successively to the code signal impulses. The lateral projection 71 of the armature 72 spans the entire series of pairs of levers 61 and 62. However, there is one bell crank lever 69 for each of the pairs of levers 61 and 62, and associated with each bell crank lever 69 and operable upon the horizontal arm thereof is one of a series of magnets 19 to 23 (the magnet 21 being shown in Fig. 2). The magnet 21 is provided with an armature 75, pivoted at 76, which carries at its extremity an adjustable screw 77 to govern the movement of the bell crank 69. Armature 75 is normally biased counterclockwise about its pivot 76 by a spring 78 extending between the armature 75 and a plate 79. The plate 79 carries therein a series of adjustable stop pins 81, one for each armature 75.

General operation

In the operation of the apparatus according to the present invention, it is assumed that the normal stop current on the line 82 is marking, in which condition the armature 72 will be seized, and the shaft 16 will be blocked against movement, in well-known manner in start-stop operation. The electromagnets 19 to 23 are energized in accordance with the code combinations sensed in the key tape. Upon receipt of the start impulse, which is a no-current impulse, the magnet 73 will be de-energized, thus releasing armature 72 to respond to the pull of the spring 74. This action initiates the rotation of the shaft 16 in a well-known manner. The cams 47 will then sequentially allow the levers 41 to 45 to respond to

the pull of their respective springs 49 unless said levers are blocked through the coaction of lugs 51 and lever arms 61 or 62. Assuming that the lever arm 43 is not blocked, it will fall into the depression in its respective cam and be caused to rotate slightly in a clockwise direction. If the lug 51 is not obstructed by a lever 61 or 62 when the lever 43 engages a cam notch 48, the lever 43 will be rotated clockwise to bring the end 52 thereof out of the arcuate path of shoulder 53 to permit the spring 57 to rotate the lever 54 to bring the shoulder 53 under the extremity 52. Then, when the cam 47 rotates further to urge the lever 43 counterclockwise, the lever 54 will be depressed against the action of its spring 57 due to the slotted hole 56. Under certain conditions of operation in response to predetermined code signals, certain of the bars 54 will function to operate certain of the stop bars 33 to control the shift movement of the type wheel 27 to cause printing in a selected one of the four rows of types. This specific mechanism is further described in said copending Zenner application.

Of course, if the projection 51 is blocked by one or the other of the levers 61 and 62 no clockwise rotation of the levers 41 to 45 will occur, and hence, the bars 54 associated therewith will not be operated downwardly. The cam assembly on shaft 16 also includes a cam 83 which acts upon bell crank lever 84, pivoted to the frame at 85, to cause a bail member 86 to act upon all of the levers 54 to return them leftwardly to their normal unlatched position (as shown), thus disengaging those members 54 which were previously engaged by the end 52 and permitting them to be returned by their springs 57 to their upward normal position with the shaft 55 at the bottom of the slot 56.

In the operation of the deciphering arrangement according to the present invention, the levers 61 and 62 are controlled jointly by the selector magnet 73 and by the deciphering magnets 19 to 23, inclusive. Having reference to Fig. 2, when the signal impulse received by the selector magnet 73 is of marking nature the magnet 73 will be energized and the armature 72 will be attracted, or moved to its counterclockwise position, to bring its laterally projecting or extending end 71 in the rightward position, as shown in Fig. 2, to actuate the lever arm 62 counterclockwise to bring its lower extremity out of register with the projection 51. Under normal conditions of operation the lever 43 would be free to rotate clockwise upon the rotation of cam 47 to bring the extremity 52 over the shoulder 53 of the bar 54. However, under the control of the deciphering arrangement according to the invention, the movement of levers 41 to 45 will be further governed by the deciphering device, exemplified by magnets 19 to 23. In the position shown in Fig. 2, the deciphering magnet 21 is shown energized under the control of its key tape, in which condition the armature 75 is attracted, to rotate the lever 69 counterclockwise to bring its laterally disposed end 68 to its rightward position, thus permitting the spring 64 to bias the arm 61 counterclockwise to bring the lower extremity thereof into registry with the vertical lug 51. Thus, when the cam 47 rotates to the position where notch 48 is in register with cam follower 46, thus to permit the lever 43 to rotate counterclockwise, such rotation will be prevented by the impingement of lug 51 against lever 61 under the control of the deciphering magnet 21.

In Fig. 6, another condition of operation is ill-

lustrated wherein the selector magnet 73 is energized by marking current on the line, and the deciphering magnet 21 is shown de-energized. In this condition of operation the energization of magnet 73 will, through the lateral portion 71 of armature 72, cause the arm 62 to be rotated counterclockwise to bring its lower extremity out of the registry with the vertical lug 51 of the lever 43. Also, the de-energization of the electromagnet 21 will permit the armature 75 to respond to the pull of spring 78 so that the lever 69 will be rotated clockwise about its pivot 63 to cause its lateral portion 68 to actuate the lever arm 61 leftwardly or clockwise against the action of spring 64 so that the lug 51 of lever 43 is not blocked, which will permit follower 46 of lever 43 to fall into the notch 48 of the cam 47, thus permitting the end 52 of lever 43 to engage the shoulder 53 of lever 54, whereby, upon further rotation of the cam 47, the bar 54 will be urged downwardly. Thus it is seen that the normal action of the lever 43 under the control of selector magnet 73 is altered by the presence of the deciphering magnet.

In Fig. 4 is shown a further condition of operation wherein the selector magnet 73 is de-energized due to spacing current on the line, and the deciphering magnet 21 is energized. In accordance with this condition, the lever arm 62 will be actuated rightwardly or counterclockwise by the end 68 of the lever 69 under the control of the deciphering magnet 21 instead of by the end 71 of the armature 72 as was the case in Fig. 6. On the other hand, the lever arm 61 is operated similarly to the manner shown in Fig. 6 except that such operation has been effected by the armature 72 of the selector magnet 73 instead of by the lever 69, as was the case in Fig. 6. Under this condition of operation, spacing current on the winding of the deciphering magnet 21 will cause the arms 61 and 62 to assume the position shown in Fig. 4 to permit the operation of the lever 43 and the consequent operation of the lever arm 54.

In the position shown in Fig. 5, the magnet 73 is shown de-energized in response to a spacing signal, and the deciphering magnet 21 is also shown de-energized. In this condition of operation, the lever arm 61 is held in a clockwise position by both the armature 72 and the lever 69, and accordingly the spring 64 acts to rotate the lever 63 clockwise against the limit stop 65 to bring the lower extremity of arm 62 into vertical registration with the projection 51 on lever 43 thus preventing the lever 43 from rotating clockwise when the follower 46 registers with the depression in the cam 47. With the mechanism just described it is seen that when the selector magnet 73 and deciphering magnet 21 assume the same condition, namely, both marking or both spacing, the lever 43 operates as it would in response to a spacing signal if it were solely under the control of the selector magnet 73. On the other hand, if the selector magnet 73 and deciphering magnet 21 are operated in opposite manner to each other, the lever 43 responds as it would for a marking signal if it were solely under the control of the selector magnet 73, which condition agrees with the table presented hereinbefore.

Transmitter

In Figs. 7 to 11, inclusive, is shown a transmitter which is keyboard operated and which transmits to the receiving device, described above, enciphered signals which, as shown previously are deciphered by the mechanism shown in Figs. 1 to

6, inclusive. Briefly, upon the operation of a key lever to transmit a character over the signal line, the signal actually represented by the key lever will not be transmitted, but such signal will be altered or changed by an enciphering arrangement which is similar in principle to the deciphering arrangement described hereinbefore.

The keyboard mechanism comprises a base portion 101 (Fig. 8) which carries therein a series of key levers 102. As is customary in such keyboards, the key levers 102 are pivotally mounted at the rear of the apparatus or base and are spring urged into their horizontal positions so that, when they are depressed, they will shift a series of five selector bars 103. The keyboard shown herein is of the type disclosed in U. S. Patent No. 1,595,472, issued August 10, 1926, to H. L. Krum. As a key lever 102 is depressed it acts upon the saw-toothed cam lugs 104 to shift the code bars 103 rightwardly or leftwardly, the code bars being slidably mounted on bearings 105.

Each of the code bars 103 is provided with a pair of studs 106 between which operates the depending arm of a lever 107 pivotally mounted on a pivot shaft 108 journaled in the bracket 109. The upper or vertically extending arm of lever 107 is provided with a laterally directed extremity 111. Also mounted on the pivot shaft 108 and individual to each lever 107 is a pair of vertically extending arms 112 and 113 between which the laterally extending extremity 111 of lever 107 cooperates. Associated with each of the pairs of levers 112 and 113 is a bell crank lever 114 which is pivoted on the pivot shaft 108. Thus, for each code bar 103 there is provided an assemblage of levers 107, 112, 113, and 114. The levers 112 and 113 are normally urged toward each other by a common spring 115. The bell crank 114 is provided with a vertically extending arm having a laterally directed extremity 116 which cooperates with the confronting edges of the arms 112 and 113. Lever 114 is normally biased in a counterclockwise direction about the pivot shaft 108 by an individual spring 117. The extremities of the horizontal arms of the bell crank levers 114 cooperate with plungers 118 of a series of solenoids 121 to 125, inclusive, of which there are five in number corresponding to the five bell crank levers 114. The solenoids 121 to 125, inclusive, are suitably mounted on mounting plates carried on posts 126 secured to the base 101. Up-stops 127 are provided for each of the solenoids to govern the movement of the plungers 118.

Each of the arms 112 and 113 is provided near its upper extremity with a shoulder 128. Cooperating with the pair of shoulders 128 is the laterally directed extremity 129 of a series of goose neck shaped contact levers 131 pivotally mounted on a pivot shaft 132 carried in the bracket 109. Each of the levers 131 is provided with a cam follower projection 133 on its horizontal arm which coacts with a transmitting cam 134 of which there are five in number in the present instance. These cams 134 are fixed to the transmitting shaft 135 which has associated therewith a toothed or grab clutch (not shown) which is a single revolution clutch, as is well known in the art. Each of the cams 134 is provided with a cam notch 136. As disclosed in the afore-mentioned U. S. Patent No. 1,595,472 the cams 134 are so disposed on the shaft 135 that their cam notches 136 are arranged in a helical series so that the levers 131 are operated sequentially. Associated with each of the levers 131 is a contact 137 which is normally open. As described in said patent a sixth cam 138 (Fig.

5) is provided, the contact lever 139 of which is so related with the cam that its contact corresponding to contact 137 is normally closed in the stop position, thus maintaining a marking condition on the signal line to which the contacts 137 are connected. Said cam 138 is known as the start-stop cam.

10 Also fixed to the cam shaft 135 is a locking bail cam 141. Cooperating with the periphery of the cam 141 is a follower roller 142 carried on an arm of the locking bail 143 which is pivoted at 144 to the frame 109. The bail 143 cooperates with the pointed extremities of the arms 112 and 113 to lock them in one or the other of the selected positions, as more clearly shown in Figs. 8, 9, 10, and 11.

15 In the operation of the transmitting mechanism shown in Figs. 7 to 11, inclusive, it is assumed that a key lever has been operated, which has moved the code bar 103 to its rightward position, as shown in Fig. 8, whereby the lever 107 is rotated to its counterclockwise position, thus causing its lateral projection 111 to actuate the arm 112 to its leftward or counterclockwise position thereby bringing its shoulder 128 out of the path of the lateral portion 129 of the contact lever 131. Thus, it is observed that the shoulder 128 of arm 112 does not during this condition of operation block the movement of the contact lever 131 to close its contact 137. However, this movement of the contact lever 131 may or may not be blocked by the companion shoulder 128 of the arm 113. In Fig. 8 the shoulder 128 of the arm 113 is shown out of the path of the portion 129 whereby the contact lever 131 is free to close its contact 137 when the cam notch 136 passes over the follower 133.

20 In the condition of operation in Fig. 8, the bell crank 114 of the enciphering device is shown in its clockwise position with its lateral portion 116 acting to urge the arm 113 to its clockwise position against the action of spring 115 to bring the shoulder 128 thereon out of operative relation or engagement with the lateral portion 129 of the contact lever 131. Thus, it is observed that the signal impulse transmitted over the line 25 through the contact 137 is of marking nature.

25 In the condition of operation shown in Fig. 9, the code bar 103 is still shown in its rightward position, thus holding the arm 112 out of the path of the projection 129 of the lever 131. However, the enciphering solenoid 125 is shown in its de-energized condition with the plunger 118 released to permit the spring 117 to rotate its associated lever 114 counterclockwise to permit the 30 spring 115 to bring the shoulder 128 of the arm 113 over the projection 129 of the lever 131, thus blocking the counterclockwise rotation of the lever 131 and precluding the closure of the associated contact 137.

35 In Fig. 10, the code bar 103 is shown in its leftward position having been operated thereto by a key lever 102. In response to this movement of the code bar 103 its associated lever 107 has been actuated clockwise to the position shown in Fig. 40 10 whereat the lateral projection 111 has moved the arm 113 to its rightward or clockwise position to bring the shoulder 128 thereon again out of the path of the projection 129 of the lever 131. The lever 114 is still shown in its counterclockwise 45 position due to the fact that the enciphering solenoid is still de-energized. The spring 117 causes lever 114 to follow plunger 118 to bring the lateral portion 116 against the arm 112 thus urging the arm 112 to its counterclockwise position, 50 bringing the shoulder 128 thereon out of the path 55 60 65 70 75 80 85 90 95

of the projection 129 of the lever 131. In this condition the goose neck lever is free to respond to the notch 136 in the cam 134 to effect the closing of its associated contact 137.

In Fig. 11 the code bar 103 is still shown in its leftward position thus holding the arm 107 in its clockwise position so that lever arm 113 is held in its clockwise position to maintain the shoulder 128 thereon out of the path of the projection 129 of the lever 131. In Fig. 11 the enciphering solenoid 125 is shown in its energized condition whereby the lever 114 is held against the backstop 145 against the action of the spring 117. In this position the lateral portion 116 of lever 114 assumes its clockwise position to permit the shoulder 128 of lever 112 to be positioned above the projection 129 of the lever 131 thus blocking the contact lever 131 against movement so that the contact 137 associated therewith remains open.

Electrical circuit

In Fig. 12 is shown an electrical circuit embracing the structures of the present invention. In the rectangle 151 is shown the transmitting contacts 137 associated with the rotary cam distributor, and the contacts 152 which are controlled by a key tape 153 or other control mechanism. It is noted that each of the contacts 152 is connected to a solenoid 121 to 125, and that the contacts 137 are included in a circuit extending from ground, through battery, then through the contacts 137 sequentially, then over the line 82, and through the winding of the selector magnet 73 to ground.

The magnet 73 is shown as included in a receiving station indicated by the rectangle 161, and the lever arms 61 and 62 are shown diagrammatically. Also shown associated with the levers 61 and 62 are the electromagnets 19 to 23, inclusive. Magnets 19 to 23 are included in a circuit extending from a common ground wire to their respective contacts 162 governed by tape controlled levers 163, thence to grounded battery.

As previously mentioned, identical key tapes 153 and 164 are provided at the transmitting and receiving stations 151 and 161, respectively. It is understood that these identical key tapes are placed in their respective tape transmitters in identical positions so that in the operation of the machine the standard tape transmitter contacts 137 and the selector magnet 73 shall have their selective operations altered in a similar manner.

Although a specific embodiment of the invention has been disclosed, it is understood that the invention is not to be restricted to the structure herein described but is to be given an interpretation determined by the scope of the appended claims.

What is claimed is:

1. In combination, means for sensing the coded record of a tape perforated according to a predetermined plan, a device for deciphering telegraphic messages electrically connected to said means, said device comprising signal controlled means responsive to received telegraph signals, a plurality of cams rotated in timed relation with the receipt of signals by said signal controlled means, a corresponding plurality of cam followers, a plurality of pairs of levers, one pair associated with each cam follower, a series of magnets connected to said sensing means for determining the position of said levers, one of said magnets associated with each pair of levers, means controlled by said signal controlled means for also governing the position of said levers, and

means actuated by said cam followers under the combined influence of said tape sensing means and said signal controlled means to control printer functions.

5 2. In a secret code receiver, an element moved according to an enciphered signal, a plurality of pairs of members settable in permuted position according to a deciphering code, means comprising instrumentalities for setting said members, and means to decipher an enciphered signal, said means controlled by the mechanical interaction of said element and said instrumentalities with said pairs of members.

15 3. In a telegraph system, a receiving station including printing means, a signal line connected to said station, selector mechanism in said receiving station responsive to received enciphered signals, said selector mechanism comprising a series of pairs of levers, and tape controlled means for controlling said pairs of said levers in a predetermined manner to decipher said received enciphered signals to control said printing means in accordance with the deciphered code signal.

20 4. In combination, receiving apparatus including printing means, selector mechanism in said apparatus responsive to enciphered signals received from a transmitting station, said selector mechanism comprising a series of pairs of blocking levers, synchronized cam means, a plurality of levers operatively related to said cam means, one associated with each pair of blocking levers, a plurality of selectable bars, one cooperable with each lever of said plurality of levers, and tape controlled means effective in conjunction with said selector mechanism to control said blocking levers to decipher said signals to effectuate, through said plurality of levers, the operation of said bars.

25 5. In combination, signal controlled means, tape controlled means, cam controlled selecting means, and a pair of blocking instrumentalities controlled jointly by said signal controlled means and said tape controlled means for controlling said selecting means to alter the signal received by said signal controlled means to effect an operation under the control of said selecting means in accordance with said altered signal.

30 6. In a deciphering device for telegraph printers, signal controlled means, an element moved according to the operation of said signal controlled means, tape controlled means, a series of elements set in permuted position according to the operation of said tape controlled means, a plurality of pairs of instrumentalities governed dually by said element and said series of elements, a set of selectable bars, cam actuated selecting means tending to select and operate said bars sequentially, and means controlled by said pairs of instrumentalities to determine the bars to be selected and operated.

35 7. In a telegraph system, a receiving station, a signal line connected to said station, tape controlled means at said station, means at said receiving station to receive enciphered signals comprising an element moved according to the nature of the received signals, a series of elements set in permuted position according to the operation of said tape controlled means, a plurality of pairs of instrumentalities governed dually by said element and said series of elements, a set of selectable bars, cam actuated selecting means tending to select and operate said bars sequentially, and means controlled by said pairs of instrumentalities to determine the bars to be selected and operated.

8. In a printer apparatus, signal responsive means, locally controlled means, a plurality of pairs of blocking elements dually controlled by said signal controlled means and said locally controlled means, cam means, members controlled by said cam means under the supervision of said pairs of blocking elements, and a plurality of bars selectively operated by said members to perform printer functions.

9. In a recorder, a plurality of pairs of blocking elements, signal responsive means for exercising a predetermined control over said pairs of blocking elements, other means for variously controlling said pairs of blocking elements, cam means, members controlled by said cam means under the supervision of said pairs of blocking elements, and a plurality of instrumentalities selectively operated by said members.

10. In combination, signal controlled means responsive to incoming signals, signal controlled deciphering means responsive to deciphering sig-

nals, cam controlled selecting means, and a plurality of pairs of controllers controlled jointly by said signal controlled means and said signal controlled deciphering means for controlling said selecting means to alter the signal received by said signal controlled means to effect an operation under the control of said selecting means in accordance with said altered signal.

EMILY Y. REIBER,

10 Executrix, Under the Last Will and Testament
of Albert H. Reiber, Deceased.
